UNITED STATES PATENT OFFICE.

ARTHUR M. BARNHART, OF CHICAGO, ILLINOIS, ASSIGNOR TO BARNHART BROS. & SPINDLER, OF SAME PLACE.

DESIGN FOR TYPE.

SPECIFICATION forming part of Design No. 18,035, dated February 7, 1888.

Application filed January 11, 1888. Serial No. 260,440. Term of patent 14 years.

To all whom it may concern:

Be it known that I, ARTHUR M. BARNHART, a citizen of the United States, residing at Chicago, county of Cook, and State of Illinois, have 5 invented and produced a new and original Design for a Font of Printing-Type, of which the following is a complete specification, reference being had to the accompanying typographic impression, which is an exact representation of said design.

The character of this design is a heavy solid-faced type, without ornamentation, and comprises capitals, figures, dollar-mark, and points. Its peculiarity is its grotesque irregularity, the letters being irregularly and inaccurately polygonal, as is most noticeable in 15 the letters C G O Q R, and having ceriphs in the form of a rough irregular hook or an

arrow-head, as A F H I J M N, &c.; also, the extremely long crosses of the E, F, and G, 20 the peculiar pipe-shaped cross of the Q, and distortion of the oval of the D by its greater convexity toward the top, all add to the grotesquely-irregular appearance of the design.

I claim—

The design for a font of printing-type herein shown and described, consisting of capitals, characters, and points, having letters irregularly and inaccurately polygonal, and whose ceriphs are irregular rough hooks or 30 arrow-heads, substantially as illustrated.

ARTHUR M. BARNHART.
